SLIDE FOR A CURTAIN ROD

Paul Koller, 4 Guggerweg, Zollikon, Switzerland

Filed July 11, 1958, Ser. No. 51,735

Term of patent 14 years

(Cl. D21—1)

Fig. 1 is a side perspective of a slide for a curtain rod showing my new design;

Fig. 2 is another perspective view showing the side opposite to that of Fig. 1; and

Fig. 3 is an end elevational view thereof.

I claim:

The ornamental design for a slide for a curtain rod, substantially as shown.
